Primary Examiner — Leah Macchiarolo*Assistant Examiner* — Christina Gabrielle Cosden(74) *Attorney, Agent, or Firm* — METIS IP LLC(57) **CLAIM**

The ornamental design for an interior part of smart door lock as shown and described.

DESCRIPTION

FIG. 1 is a perspective view of an interior part of a smart door lock according to our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The short dash-dash broken lines indicate portions of the interior part of the smart door lock that form no part of the claimed design.

1 Claim, 7 Drawing Sheets(56)
